DELIVERY BOX

John A. Hopwood, Great Neck, N. Y.

Application November 30, 1934, Serial No. 755,343

5 Claims. Cl. 217—19

This invention relates to delivery boxes and is adapted especially for incorporation in boxes for the retail delivery of bottled milk.

In this art, the so-called slat box has become quite popular and is generally preferred by the larger milk distributors. These boxes embody a rectangular body formed by superimposed slat frames which are maintained in assembled relation in various ways. For example, in some types of box, the slats of each frame are secured together at the corners and to the slats above the frames by metal corner angles to which the slats are attached. The more widely used structures of this kind are those wherein the slats are secured to metal corner angles by so-called lacing wires or rivets which pass vertically through the slats of the several superimposed courses in succession and through the corner angles to hold the parts together.

A box thus constituted embodies a strong and durable construction, but has presented a number of rather serious problems. For example, it is the common practice to collect empty bottles in delivery boxes, frequently in inverted position in the boxes, and to pass these bottles directly through the washers without removing them from the boxes in order to facilitate the handling of bottles collectively. In the washing operation, the bottles are subjected to live steam and scalding water, and as a result boxes are wet during such operation. Thus, in the normal use of the box, it is wet during the washing of the bottles and after washing, the boxes and bottles are set aside and proceed to dry. Subsequently, the bottles are filled with milk, sealed, and ice packed about the necks, so that the boxes are again wet and remain so until the ice is melted and the boxes again proceed to dry.

The wood from which such boxes are made is thus alternately wet and dry throughout the life of the box and there results alternate periods of swelling and contracting of the wood thereof. It will of course be remembered in this connection that when wood is wet, it swells or expands in a direction normal to the grain. There is very little, if any, longitudinal expansion, but lateral and vertical expansion of the slats is appreciable. When the wood dries out, the slats again contract with the result that there is practically a constant expansion and contraction which must necessarily occur in use of wood for the purposes stated.

When wooden slats are confined within corner angles and riveted or bolted together as stated, this expansion and contraction of the wood is apt to cause serious difficulty. For example, if the

box is manufactured with the wood in dry state and the rivets pulled down tight, the subsequent swelling of the wood, when wet, is not only apt to, but usually does either shear off the rivet heads, pull them through the corner angles, stretch the rivets undesirably or to a point of breakage or cause splitting of the corners in a manner hereinafter more fully explained. Suffice it here to say that practice has demonstrated that such is the case.

As a result, it has become almost the universal practice in the use of slat boxes to space the slats apart either by spacers formed on the corner angles or by independent spacers of relatively small size.

The difficulty with these arrangements is that when the box is wet, the spacers are either undesirably deformed or the wood yields to permit embedding of the spacers therein. Splitting of the slats frequently results, but, in any event, the box loosens materially when the wood dries making a very noisy box due to rattling in use.

With the foregoing considerations in mind, and as a result of exhaustive research in order to obviate and ameliorate these conditions, I have discovered that it is possible to eliminate spacers and at the same time make use of the inherent character of wood to permit the box to be made tight at its corners at all times and yet permit of such expansion in the walls of the box as must necessarily occur when the wood thereof is wet.

This I accomplish by clamping the slats or bars of the box in edge abutting relation at the four corners of the box and between metal limiting elements tied together by bolts and rivets and overlying the end portions of the bars or slats, whereas those portions of the bars or slats which are not directly between said limiting elements are made of decreased height to provide, between contiguous edges of the bars, expansion space which will permit the slats to expand in a vertical direction without engagement of these parts of adjacent slats with one another. By this arrangement, the building up of leverage, as will be hereinafter more fully explained, and which I have found to be the primary cause of rivet breakage and splitting in prior boxes, is entirely eliminated, the rivets of the present invention taking merely the direct thrust which is not sufficient to cause damage to the structure.

Features of the invention, other than those adverted to, will be apparent from the herein-after detailed description and claims, when read in conjunction with the accompanying drawings.

The accompanying drawings illustrate one practical embodiment of the invention, but the construction therein shown is to be understood as illustrative, only, and not as defining the limits 5 of the invention.

Figure 1 is a fragmental perspective showing one corner of a slat box illustrative of the type of box to which the present invention relates.

Figure 2 is a side elevation of the structure 10 shown in Figure 1, illustrating the manner in which expansion of the wooden slats results in breakage.

Figure 3 is a fragmental perspective showing the effect of expansion in a greatly magnified 15 form.

Figure 4 is a side elevation showing clearance for expansion.

Figure 5 is a side elevation of one corner of 20 a box showing the manner in which the box of the present invention is made to preclude breakage.

Figure 6 is a section on the line 6—6 of Figure 5.

Figure 7 is a view similar to Figure 5, but 25 illustrates the slats expanded under the influence of moisture.

Figure 8 is a section on the line 8—8 of Figure 7 showing expansion greatly exaggerated in the interest of clearness.

Figure 9 shows diagrammatically the theory 30 in accordance with which the present invention functions.

In Figure 1 of the drawings, I have illustrated, 35 in perspective, one corner of a slat box 1. Such a box embodies superimposed slats 2 abutting at the corners of the box in any appropriate way. Such a box may be provided with corner irons serving to enclose the corners of the box to cover and protect the same. However, these corner 40 irons have been omitted in the present showing.

In practice, such boxes are generally provided at their upper and lower edges and at each of their four corners with metal limiting members 3, shown as angle irons and these limiting members 45 are perforated to receive rivets or tie rods 4 which are passed therethrough and through the several slats 2 in succession. These rivets thus extend for the full height of the box and are headed over at their opposite ends as indicated at 5.

50 In practice the limiting members 3 may be made integral with and form part of the metal corner closures. However, for the purpose of the present showing, they are illustrated as separate and independent.

55 The box thus formed appears in side elevation, as shown in Figure 2, and is initially made as shown in full lines in said figure, the slats 2 being in edge abutting relation and clamped firmly against one another by the limiting members 3 held in place by the tie bolts or rivets 4.

When a box of this kind, however, is wet, the 60 wood from which the bars 2 is made is susceptible to marked expansion, so that in a box with slats 2" or 3" in height, the expansion, if not restricted by limiting means of any kind, will not infrequently exceed $\frac{1}{2}$ " to $\frac{3}{4}$ ". The structure shown in Figure 2 is such that it, structurally, cannot stand this strain. As a result, the rivet heads are broken off or the bars are 65 split or the rivets are stretched and broken.

70 As a result, attempts to make the box, such as shown in Figures 1 and 2, has been given up as impractical and manufacturers have turned to the arrangement shown in Figure 4 which consists in spacing the slats 2 apart to leave inter-

spaces 6, generally maintained by spacers 4a, which vary considerably in structure. The principle, however, underlying the operation of these spacers is the same. They simply serve to space the slats apart, so that when expansion takes place the slats can expand. The difficulty, however, with this arrangement is that when the slats expand, they force the spacers into the wood and generally split the slats.

My research in connection with boxes of the kind shown in Figures 1 and 2 convinces me 10 that boxes of this kind fail due to the application of great leverage which, in practice, is more than the rivets and limiting members can withstand.

15 Wood is a fibrous substance. It comprises an infinite number of relatively small fibers which extend generally in the direction of the grain of the wood and each of which is substantially tubular in form. When the wood is dry, the 20 fibers are individually contracted, but, when the wood is subjected to moisture or water, these fibers take up the water and expand radially. While the fiber of wood has not a truly circular 25 cross section, I have in Figure 9 attempted to show schematically what takes place. In this figure, 7 indicates the normal size of a dry wood fiber which, upon being wet, expands radially in all directions to a larger diameter shown at 7a, thus making the fiber larger and when this 30 occurs in all of the fibers of a piece of wood, the aggregate of expansion, while minute in each, becomes very considerable for the whole. If wood is unrestricted, the expansion will be in all 35 directions, but I have found that it is possible to restrain it in one direction if it is permitted to expand in another direction. Thus, by reference to Figure 9, assume that 3 are abutments or limiting members between which the wood fibre is positioned. 7 indicates the normal outline of 40 the dry fiber. If moisture is applied to this fibre, and it proceeds to expand or swell, it will be found to enlarge laterally while maintaining substantially its same vertical height. What is true 45 with one fiber occurs with the several fibers of a piece of wood, and the wood will expand laterally if it is firmly held between abutments against expansion vertically.

Theory therefore indicates that it is thoroughly practical to confine wood against expansion in 50 one direction at least within reasonable limits providing limiting members of appropriate strength are provided. I have discovered that the difficulty with the box of Figure 2 resides in the fact that the thrust of the swelling wood is 55 not taken by the limiting members as purely a direct thrust of the interposed fibers, but rather through the greatly increased force resulting through the action of leverage. This I have attempted to show in Figure 2 of the drawings on 60 a greatly enlarged scale in order that the same may be clear.

By reference to Figure 2, the reference character 8 indicates a line drawn midway between the upper and lower edges of the box and which may 65 be referred to as a neutral plane. When the wood is wet, the wooden parts of the box above the line expand upwardly, while the wooden parts of the box below the line expand downwardly. Thus, the upper edge of the middle slat 2 will expand upwardly, as indicated by the dotted line 70 2a, causing the next slat above to be bent upwardly intermediate its ends, while at the same time, said superimposed slat will also expand, so that its upper edge will occupy the position 75

2b causing the top slat to be further bent upwardly, and it will simultaneously expand so that its upper edge 2c will be very appreciably raised. At the same time, the same effect is occurring 5 in a downward direction, each slat undergoing the change shown in Figure 3 in a greatly exaggerated manner. For example, the vertical zone between the edge 9 and the line 10 in Figures 2 and 3 is the zone of limitation between the limiting members 3, and in this zone the fibers will 10 expand laterally, as indicated by the dotted lines 11, while beyond this zone of limitation, the slats will expand vertically, as indicated by the dotted lines 2a, 2b and 2c. The practical result of this 15 arrangement is that each of the two upper bars constitutes in effect a lever of the first class fulcrumed at the point 12 and with a power arm indicated at 13 and extending for practically half the length of the box. The maximum of force 20 is exerted upon this power arm about the middle of the length of the box and is indicated by the arrows 14. The arrows 15 indicate the work done by this lever which obviously constitutes the building up of a relatively great vertical force upwardly against the upper limiting member 3 and 25 downwardly against the lower limiting member 3.

As a result of this great force built up through leverage as described, rivet heads cannot stand the pressure and they break. If they do not 30 break, the slats will split or the rivet heads will pull through the limiting members. Something must "give" and breakage results.

As a matter of actual practice, the vertical expansion and bending of the several superimposed slats produce so great a force of leverage as to 35 actually cause lateral deflection or bending of the bolt or rivet 4, as shown in dotted lines in Figure 2, and the actual limiting effect of the members 3 in the limiting zone and adjacent the line 10 is 40 somewhat relieved permitting further expansion in this zone which is undesirable and tends to further bring about lateral deflection of the bolt as stated.

Graphically stated, the several slats of the box 45 may be said to "fan", with respect to the bolt, bringing about the bending of the bolt with accompanying stretching thereof. Unless the bolt is of very unusual size and strength, the head will break off or the bolt will break intermediate its 50 length as indicated in dotted lines in the figure. There is generally an accompanying deformation of the limiting plates 3 which occurs prior to breakage and even though the parts hold and do not break, when the box is dried out and the slats 55 tend to reassume their normal position, the bolt will be bent back into substantially straight position leaving a loose jointed structure. When this occurs frequently, as the box is wet and dry, the fatigue on the bolt is not only destructive thereto, 60 but the wooden parts of the box cannot stand the strain and split.

My study and research have shown that the wood in the limited zone between the lines 9 and 65 10 can be properly confined by rivets or limiting plates, if the thrust is direct and is not accompanied by the building up of great pressures under leverage, but practice has demonstrated that where the leverage occurs breakage results.

Thus, in carrying out the present invention, I 70 clamp the ends of the slats together at the corner of the box by ties or rivets 4 and limiting plates 3, as hereinbefore described, and as shown in Figure 5, so that the slats are actually in edge abutting relation within the limiting zone indicated by the lines 9 and 10, but beyond the line 75

10, one or both of the adjacent edges of each two slats is cut away as indicated at 16, to provide expansion spaces 17. In practice the adjacent edges of both slats may be cut as stated, but, in the interests of economy, I find it convenient to 5 cut the opposite edges of every alternate slat. In this way, the first, third and fifth slats may be left with straight edges, while the second and fourth slats may be cut as stated, but, in any event, the slats should be cut away to such extent that the aggregate cut out of the several slats will at least be equal to the aggregate expansion of said slats. In other words, the sum of the vertical dimensions of the cut outs should be at least 10 equal to the sum of the vertical expansion of the several slats 2. For example, and without intending to limit the invention to specific dimensions, I may state that in a box made from ash wood with five slats $\frac{3}{4}$ " to 1" thick, and approximately 2" high, the cut outs between each 20 two slats can conveniently be approximately $\frac{1}{8}$ ". This will allow the wood to expand between the line 10 at one end of the box, and a corresponding line at the other end of the box for a maximum vertical expansion of $\frac{1}{2}$ " at joints without 25 setting up the leverage to which I have hereinbefore referred.

Consequently, when the slats are expanded to substantially close these openings 17, as graphically shown in Figure 7, the only vertical pressure between the slats will be at the ends which are confined within the limiting zone between the limiting plates 3 and the autogenous pressure thereby set up will be in a truly vertical direction, so that there is no leverage increase in power 30 and the ends of the slats within this zone are free 35 to expand laterally as indicated at 11 in Figures 8 and 3.

Practice has demonstrated that ordinary box 40 hardware will effectually withstand the expansion to which I have referred when used in conjunction with the present invention. If the same hardware were put on a box, as shown in Figure 2, breakage will result.

The advantage of this invention is that it permits not only expansion without breakage, but when the wood dries out, the box will not be loose, but will remain tight for all practical purposes. Furthermore, as the slats bear against one another within the limiting zone, for substantially 50 their full thickness and for the full length of the zone, there is no localized application of pressure which would damage the wood fiber or cause splitting, and consequently, there is an even distribution of the forces to which the slats are subjected 55 in this zone and they are well able to withstand these forces. There results a box which is tight at its corners at all times, which does not require the use of spacers, which does not build up destructive leverage and which is thoroughly practical and durable. The stresses and strains to which the box is subjected by atmospheric changes or by the presence or absence of water are properly distributed and the corner construction is sufficiently strong and durable to stand the hardest usage. 60

The foregoing detailed description sets forth the invention in its preferred practical form, but the invention is to be understood as fully commensurate with the appended claims. 65

Having thus fully described the invention, what I claim as new and desire to secure by Letters Patent is:

1. A milk delivery box comprising a plurality of superimposed courses of wooden slats, limit- 75

- ing members positioned at each of the four corners and at the upper and lower edges of the box and overlying end portions of the upper and lower slats to define vertically limiting zones, tie 5 members extending vertically through the slats in the limiting zones and anchored with respect to the limiting members to clamp those portions of the several slats which occupy the limiting zones in edge abutting relation, at least one edge 10 of each two adjacent slats being cut away between substantially the limiting zones at the opposite ends thereof to provide an expansion space of sufficient height to preclude forcible contact between adjacent slats exteriorly of the limiting zones. 15
2. A milk delivery box comprising a plurality of superimposed courses of wooden slats, corner angles positioned at each of the four corners and at the upper and lower edges of the box and over- 20 lying end portions of the upper and lower slats to define vertical limiting zones, tie members extending vertically through the slats in the limiting zones and anchored with respect to the corner angles to clamp those portions of the several 25 slats which occupy the limiting zones in edge abutting relation, at least one edge of each two adjacent slats being cut away between substantially the limiting zones at the opposite ends thereof to provide an expansion space of sufficient height 30 to preclude forcible contact between adjacent slats exteriorly of the limiting zones.
3. A milk delivery box comprising a plurality of superimposed courses of wooden slats, corner angles positioned at each of the four corners and 35 at the upper and lower edges of the box and overlying end portions of the upper and lower slats to define vertical limiting zones, elongated rivets extending vertically through the slats in the limiting zones to clamp those portions of the sev-

eral slats which occupy the limiting zones in edge abutting relation, at least one edge of each two adjacent slats being cut away between substantially the limiting zones at the opposite ends thereof to provide an expansion space of sufficient height to preclude forcible contact between adjacent slats exteriorly of the limiting zones. 5

4. A milk delivery box comprising walls formed of superimposed wooden slats in edge abutting relation adjacent their opposite ends and free 10 from engagement with one another for the remainder of their length to leave spaces between said slats greater than that to be taken up by expansion of the wood of the slats when wet, limiting members positioned at the four corners of 15 the box and at the upper and lower edges thereof and substantially co-extensive with the edge abutting portions of the slats, and tie members extending through the several superimposed slats and through the limiting members to tie said 20 limiting members together and hold the abutting portions of the slats in engagement with one another.

5. A milk delivery box comprising walls formed of superimposed wooden slats in edge abutting 25 relation adjacent their opposite ends and free from engagement with one another for the remainder of their length to leave spaces between said slats greater than that to be taken up by expansion of the wood of the slats when wet, corner angles positioned at the four corners of the box and at the upper and lower edges thereof and substantially coextensive with the edge abutting portions of the slats, and tie members extending through the several slats and through 30 the corner angles to tie said corner angles together and hold the abutting portions of the slats in engagement with one another. 35

JOHN A. HOPWOOD.
